H. J. LEBHERZ ET AL

BOTTLE CAPPING TOOL

Filed Feb. 8, 1927

UNITED STATES PATENT OFFICE.

HARRY J. LEBHERZ AND ROBERT W. LEBHERZ, OF FREDERICK, MARYLAND, AS
SIGNORS TO THE EVEREDY COMPANY, OF FREDERICK, MARYLAND, A CORPORA-
TION OF MARYLAND.

BOTTLE-CAPPING TOOL.

Application filed February 8, 1927. Serial No. 166,696.

Our invention relates broadly to bottle capping tools and more particularly to a construction of frame for a bottle capper with an upwardly extending rack member for the 5 adjustment of a slidable carrier thereon.

One of the objects of our invention is to provide a construction of frame for a bottle capper for facilitating the manufacture and production of bottle capping tools for guiding an adjustable rider into a position for effecting successive bottle capping operations.

Another object of our invention is to provide a construction of standard for a bottle capping tool in which a pair of strip members are positioned at right angles to each other for providing a rack at the upper extremity thereof on which a carrier may be vertically adjusted, the assembly of the strip members being such that the rack and standard may be formed on a quantity production scale at small cost.

Other and further objects of our invention reside in the construction of a bottle capper frame which lends itself readily to manufacturing processes by a minimum number of casting or pressing operations.

Our invention will be more clearly understood from the specification hereinafter following by referring to the accompanying drawings in which:

Figure 1 is a side elevation showing the bottle capper frame of our invention partially broken away and illustrated in cross-section; Fig. 2 is a front view of the bottle capper frame of our invention with the base thereof shown in cross-section looking in the direction of line 2-2 of Fig. 1; Fig. 3 is a cross-sectional view taken through 35 the standard of the bottle capper frame on line 3-3 of Fig. 1; Fig. 4 is a plan view illustrating the pressed base of the bottle capper frame, a cross-sectional view being taken on line 4-4 through the standard of Fig. 40; Fig. 5 is a fragmentary cross-sectional view taken through the frame and base of the bottle capper on line 5-5 of Fig. 45; and Figs. 6 and 7 are cross-sectional views taken through the vertical standard on lines 50 6-6 and 7-7, respectively, of Fig. 1.

Heretofore in the art it has been usual to provide a special casting for the vertical standard constituting the frame of a bottle capping tool requiring special patterns and

processes of casting which normally involve 55 undesirable manufacturing costs when considering manufacture on a quantity production scale. By our invention we have developed a frame for a bottle capping tool which may be manufactured inexpensively 60 and by a minimum number of manufacturing operations thereby reducing cost of labor and facilitating manufacture.

Referring to the drawings in detail, reference character 1 designates a pressed metal 65 base for the bottle capping tool having an upstanding pressed portion 3 with an integral flat flange 2 connected therewith. The base is provided with an intruded central rib 4 which extends in the direction of the narrower portion 5 of the base. A standard 70 consisting of strip members 6 and 8 is arranged on the base in the manner illustrated. The strip members are flat and positioned at right angles one to the other. The strip member 6 which extends in a plane perpendicular to the longitudinal axis of the base is anchored to the base by means of rivets 7 and is apertured as represented at 6^a, 6^b, 6^c, 6^d and 6^e. The apertures are in the nature 75 of slots through which portions of the vertically extending strip member 8 pass. The strip member 8 passes wholly through the strip member 6. Its central portion 10 is so shaped that the strip member 8 passes wholly 80 through the longitudinal slot 6^a in such manner that a lug formed on the lower portion of the strip member at 9 extends through the base 5 and is anchored at 9^a in the base and at 8^e through the aperture 6^e. The upper 85 portion of the strip member 8 is anchored at 8^a, 8^b, and 8^c through the apertures 6^a, 6^b and 6^c. Reinforcing the upper portions of the strip 90 8 we provide a rack member 11 which is positioned parallel to the upper portion of the strip member 8. The member 11 is secured in the strip member 6 by means of lugs which extend through the apertures 6^a, 6^b and 6^c parallel with the lugs 8^a, 8^b and 8^c on strip member 8. The lugs on strip member 100 11 are upset or flattened as represented at 11^a in Fig. 3 for forming a rigid connection between the strip 11 and the strip 6. Both the strip member 8 and the strip portions 11 are cut to form a rack 12 along which the 105 carrier 14 is arranged to slide vertically. The carrier 14 supports a capping throat 15 and the carrier is actuated by a hand lever

17 under control of a spring member 16 in such manner that the carrier may be pressed downwardly for performing successive capping operations and returning to its original 5 position after each operation.

In the assembly of the bottle capper frame the strip member 8 is protruded through the apertured portion in strip member 6 in a direction substantially at right angles to the 10 strip member 6. The strip member 8 is next swung in a small arc until the edges of the strip member 8 abut with the face of the strip member 6. The lug portions 8^a, 8^b and 8^c of the strip member 8 protrude through 15 the apertures 6^a, 6^b, 6^c and 6^d in the strip member 6 which are aligned therewith in a predetermined order. The lugs 8^a, 8^b, 8^c and 8^d are then upset providing a securing 20 head for rigidly anchoring the strip 8 with respect to the strip 6.

It will be observed that the bottle capper frame is extremely simple in its assembly and that the entire frame may be made by casting or pressing operations with an expenditure of minimum time and labor.

While we have described our invention in a certain preferred embodiment, we desire that it be understood that modifications may be made and that no limitations upon our invention are intended other than are imposed by the scope of the appended claims.

What we claim as new and desire to secure by Letters Patent of the United States is as follows:

35 1. A frame structure comprising a metallic base and a standard mounted on said base, said standard comprising a pair of strip members, said strip members extending at right angles one to the other with one of said strip members passing through 40 the central portion of the other of said strip members and provided with a rack in the upper portion thereof for guiding a slidable carrier thereon.

45 2. A bottle capping tool comprising a base member, a standard carried by said base member and consisting of a pair of strip members one of said strip members being disposed in a plane at right angles to the other of said strip members and passing through said first mentioned strip member and secured at its lower end to said base for providing a brace for said first mentioned strip member at its lower end and providing a rack at its upper end for guiding a slidable carrier thereon for effecting capping operations.

55 3. A bottle capping tool comprising a base

member, a standard positioned adjacent one end of said base member, said standard comprising a pair of strip members disposed in planes at right angles one to the other, with one of said strip members in a plane perpendicular to the longitudinal axis of said base member and the other of said strip members parallel with the longitudinal axis of said base member and passing through said first mentioned strip member and providing a brace at the lower end of said first mentioned strip member and a rack in the upper end of said first mentioned strip member for guiding a carrier thereover for successive bottle capping operations.

4. A bottle capping tool comprising a base member, a pair of strip members extending vertically from said base member, one of said strip members being disposed in a plane at right angles to the longitudinal axis of said base member and the other of said strip members being disposed in a plane coincident with the longitudinal axis of said base member, said last mentioned strip member passing centrally through said first mentioned strip member and being anchored at its lower end to said base member and provided at its upper end with a rack, said second mentioned strip member being anchored to said first mentioned strip member at a plurality of points along the length of said first mentioned strip member, said rack providing a guide for a carrier arranged for successive capping operations.

5. A bottle capping tool comprising a base member, a pair of vertically extending strip members, one of said strip members extending at right angles to the longitudinal axis of said base member and being slotted along the length thereof, a second strip member being positioned in a plane coincident with the longitudinal axis of said base member, said second strip member being anchored to said base member and passing centrally through said first mentioned strip member and providing a rack at the upper portion thereof, said second mentioned strip member having lugs positioned to project through the apertures in said first mentioned strip member and a carrier positioned upon the upper portion of said strip members and having means for engaging said rack for successive capping operations.

In testimony whereof we affix our signatures,

HARRY J. LEBHERZ.
ROBERT W. LEBHERZ.
